CONTROL DEVICE FOR RADIO RECEIVING APPARATUS

Benjamin Franklin, Haynesville, Va., assignor,
by mesne assignments, to Mark S. Willing,
Mount Holly, Va.

Application March 10, 1936, Serial No. 68,109

3 Claims. (Cl. 250—20)

This invention relates to a control device for radio receiving apparatus wherein broadcasting programs of various stations will be selectively tuned in on the apparatus over any given period 5 of time during each twenty-four hours.

Another object of the invention is to provide a control attachment of this character wherein the tuning in devices or variable condensers are manually adjustable so as to accurately set them 10 and thus obtain the best possible tones over the apparatus.

Another object is the provision of a control attachment of comparatively simple and inexpensive construction which is composed of relatively sturdy parts not likely to get out of order 15 and which does not require any minute movements in any of the mechanically operable portions thereof.

More specifically, the invention contemplates 20 a control mechanism or attachment for radio receiving apparatus wherein a plurality of variable condensers or tuning in devices are provided in conjunction with mechanically operable means for rendering said condensers operable individually and in a sequence depending upon the 25 broadcasting programs which the user desires to obtain. In other words, the present apparatus comprises a plurality of variable condensers, there being a condenser for each broadcasting 30 station the user desires to tune in on, and mechanically operable means for rendering the individual condensers operable in any desired order. Thus, after each condenser is set, so to speak, at the point where it will best receive the program 35 being broadcast from a given station, the several condensers are mechanically rendered operative in any desired order, so that the desired portions of the programs from the several stations will be received on the receiving apparatus. For instance, the program from the same station may 40 be tuned in on the apparatus any number of times during the day and will always be clearly received by reason of the fact that the several condensers are manually set, so that they operate with maximum efficiency.

With these and other objects in view, the invention consists in certain details of construction and combinations and arrangements of parts, all 50 as will hereinafter be more fully described and the novel features thereof particularly pointed out in the appended claims.

In the accompanying drawings—

Figure 1 is a front elevational view of the upper 55 portion of a radio receiving apparatus cabinet

illustrating more or less diagrammatically the present control attachment;

Fig. 2 is an elevational view of the control dial and cooperating rotating contact arm for rendering the several tuning in devices individually 5 operable;

Fig. 3 is a vertical sectional view through the structure illustrated in Fig. 2 and the front wall of the cabinet;

Fig. 4 is a diagrammatical illustration of the 10 manner in which the several condensers are individually coupled into circuit by the present control attachment; and

Fig. 5 is a detail sectional view on the line 5—5 of Fig. 2. 15

In the present illustration, three tuning in devices or variable condensers are illustrated at A, B and C, respectively, the same being manually adjustable by the knobs A', B' and C' at the exterior of the cabinet 10. Mounted on the inner 20 surface of the front wall of the cabinet is a support 11 having contact elements for connecting into the condenser circuit of the apparatus any one of the several condensers illustrated and also for closing the tube circuit of the receiving apparatus in synchronism with the closing of the individual circuits through the condensers. Preferably, these contact elements are circular and arranged concentrically with one another. The tube circuit is indicated as comprising leads 12 30 and 13, which are attached to the two inner circular contact rings 14, 15, on support 11 and arranged on said support concentric with contacts 14, 15, are two sectional contact rings 16, 17, the length of the individual sections of each of these 35 last two rings corresponding to a desired period of time for purposes which will hereinafter appear. A shaft 19 adapted to be rotated through gears 20, 21 and 22 from a clock mechanism 23, has an arm 18 mounted thereon and mounted on said arm are contact pieces 24, 25, 26 and 27. Contacts 25 and 26 are connected together by wire 28 and contact pieces 24, 27, are connected together by wire 29. Also, contacts 25, 26, engage the circular contacts 15 and 16, while contacts 24, 27, engage the circular contact rings 14 40 and 17. Connected to each one of the sections of ring 16 is a contact member 30 and connected to each of the sections of ring 17 is a flexible finger 31 also constituting a contact member. Normally, these contacts 30, 31, are separated but the contacts for any pair of sections can be brought into engagement by means of a plug 45 insertable through any one of the series of openings 32 in the front wall of the cabinet, there being an 50

55

opening in the cabinet for each pair of contact ring sections. In the present instance, each section of contacts 16, 17, represents the distance arm 18 will be rotated in one hour's time, there being twenty-four sections in each of the rings 16, 17, and the gearing through which the arm is rotated being so proportioned that said arm will make one complete revolution every twenty-four hours. However, it will be appreciated that the length of the individual sections of rings 16, 17, may be reduced to represent fractions of hours.

Near the perimeter of support 11 are two additional contact rings, the outermost ring 33 being continuous and the other ring 34, arranged concentrically radially inward of ring 33, being made in sections corresponding to the sections of rings 16, 17. Also mounted on arm 18 are two contact members 35, 36, connected to each other by wire 37 and these contacts are adapted to engage ring 33 and the sections of ring 34, respectively. Extending from ring 33 is a line 38 which constitutes one side of the condenser circuit whose leads are shown at 39, 40, and the plugs, which are inserted through openings 32, each carry a contact band 41 adapted to engage a contact finger 42, there being a finger 42 connected to each section of contact ring 34. A wire 43, of course properly protected, extends from the contact band 41 of each plug and is adapted to be secured to the binding post 44 of any one of the several condensers.

Referring particularly to Fig. 4, the apparatus is illustrated as being connected up for controlling the reception of two radio programs from each of three broadcasting stations. Assuming the uppermost aperture, denoted at X, represents the position of arm 18 at six o'clock a. m., the plug P¹ in the next aperture will cause the condenser B to be cut into circuit at seven o'clock. At that hour, the condenser circuit would run from line 39 to line 38, contact ring 33, contact 35, wire 37, contact 36, one of the sections of contact ring 34, finger 42, plug P¹, wire 43, binding post 44, wire 45 to condenser B, and from said condenser by line 46 to line 40. At the time the arm 18 established the circuit at six o'clock, as above outlined, the tube circuit would be closed through the four inner contact rings and would be opened at the expiration of the hour as will be readily understood. At the expiration of the hour the program from that particular station will be cut off due to the fact that arm 38 would then move into engagement with sections of the several contact rings that were not connected by reason of the absence of a plug. Still referring to Fig. 4, it will be seen that at noon the same circuit would be established by reason of one of the plugs, P², having been inserted to close the contacts 30, 31, for the tube circuit and to also close the circuit for the condensers through the contact finger 42 and the contact band 41. At three o'clock p. m., the circuit will be closed through condenser A, by reason of plug P³, inserted in the opening 33, representing that hour, and said circuit will be broken at four o'clock, but re-established at six o'clock p. m., by reason of plug P⁴. On each of these occasions, the tube circuit will also be closed, as previously described. At the time the circuit is closed through condenser A, it comprises lead

39 and line 38 to contact ring 33 and from the section of ring 34 corresponding to the hours designated through the plug and wire 43 to binding post 44 of condenser A, and from said condenser through line 47 to lead 40 of the condenser circuit. Also, as shown in Fig. 4, the tube circuits and the circuits for condenser C will be closed by reason of plugs P⁵ and P⁶, respectively. It will be appreciated that any number of plugs may be used for cutting in, so to speak, the radio any number of times during the day. The binding posts or other means of attaching the wires 43 to the several condensers may be made to accommodate any number of connections and, likewise, any number of condensers may be used, depending upon the number of stations it is desired to listen in on, one condenser being used for each station. It will also be apparent that any one station may be cut in on any desired number of times during the twenty-four hours. By the present arrangement, the user need only adjust the several condensers to a point where the best reception will be had from the several broadcasting stations, and then insert the plugs in the openings 32 corresponding to those hours of the day when he wishes to listen in on the several stations, whereupon the desired programs will be received without further effort on the part of the user. The manual manipulation of the variable condensers insures efficiency in the reception.

In the event the automatic control is to be dispensed with, a switch indicated at 56 is closed to establish the circuit through condenser A, and all plugs are removed from the control dial.

What I claim is:

1. Radio apparatus comprising a plurality of condensers each adapted to tune said apparatus to a predetermined frequency, a control mechanism for said apparatus comprising a plurality of groups of contact members adapted to control the power circuit of said apparatus, a switching element movable to sequentially engage the contact members of each of said groups and an additional contact member engageable by said switching element and adapted to be connected to one of said condensers, a plug element connected to each condenser and engageable with said additional contact member, and means responsive to engagement of said plug member to prepare a circuit with said power control contacts whereby said switching element will simultaneously complete the power circuit and connect the condenser.

2. Radio apparatus such as set forth in claim 1 wherein the groups of power circuit control contacts and said additional contact member are concentrically arranged and said switching element is rotated by a clock mechanism to engage said contact members.

3. Radio apparatus such as set forth in claim 1 wherein the means responsive to engagement of the plug member for preparing the circuit with the power control contacts consist of a pair of normally separated contact members, one of which is engaged by said plug member and moved by said plug into engagement with the other of said pair.

BENJAMIN FRANKLIN.
